STITCHDOWN SHOE

Harry N. Grimes, Brentwood, Mo., assignor to
 United Shoe Machinery Corporation, Borough
 of Flemington, N. J., a corporation of New Jersey

Application October 6, 1939, Serial No. 298,289

3 Claims. (Cl. 36—16)

This invention relates to improvements in stitchdown shoes and sole units for use in such shoes.

In the manufacture of stitchdown shoes very little attention has been paid heretofore to shaping and strengthening the bottoms of the shoes in the shank portions thereof and as a result stitchdown shoes have generally been devoid of many wearing and foot-fitting qualities which are characteristic of other and more expensive types as well as lacking in character and refinement in their shank portions.

An object of the present invention is to improve the construction and appearance of the shank portions of the bottoms of stitchdown shoes without substantially increasing the expense of manufacturing the shoes.

In accomplishing this object, a stitchdown shoe has been produced in which the shank portion of the shoe bottom has been strengthened and shaped to reproduce certain desired characteristics of last bottom contour by the employment in the shoe of a sole unit of novel construction. The illustrated sole unit comprises an extension edge sole, i. e., a sole the marginal portion of which is extended to underlie the outturned flange of the upper of a stitchdown shoe, a relatively stiff reinforcing piece which is secured to one side of the sole, and a longitudinally curved shank stiffener which is interposed between the reinforcing piece and the sole. As shown the reinforcing piece covers the heel and shank portion of the sole with the exception of the extension margin thereof and the reinforcing piece together with the portion of the sole to which that piece is applied are curved both longitudinally and transversely in conformity with the longitudinal and transverse curvatures of the last bottom. The extension edge portion of the sole, however, is left uncovered and without any substantial transverse curvature for the reception of thread lasting and outsole-attaching stitches.

The invention will be described with reference to the accompanying drawing, in which

Fig. 1 is a perspective view of my improved sole unit showing the upper or foot-facing side of the unit;

Fig. 2 is a perspective view of the unit showing the lower or outsole-facing side thereof;

Fig. 3 is a sectional view of the unit taken along the line III—III of Fig. 1 and illustrating the operation of molding the unit;

Fig. 4 is a cross-sectional view of the shank portion of a three-sole stitchdown shoe in which

my improved sole unit is embodied in place of the usual middle sole;

Fig. 5 is a perspective view, partially broken away, of the shoe shown in Fig. 4; and

Fig. 6 is a fragmentary cross-sectional view of the shank portion of a two-sole stitchdown shoe embodying my improved sole unit.

Referring to the drawing, my improved sole unit is adapted for use in place of the usual insole in a two-sole stitchdown shoe or in place of the usual middle sole in a three-sole stitchdown shoe. When used in a three-sole stitchdown shoe my improved sole unit may be termed a middle sole unit (and the sole member of the unit may be termed a middle sole) inasmuch as the unit is located between an insole and an outsole. In such a shoe, however, the sole unit may aptly be also referred to as an innersole unit inasmuch as the unit occupies an inner position with respect to the outsole or tread sole of the shoe. Broadly considered, therefore, my improved sole unit is an inner sole unit regardless of whether it is to be used in a three-sole or in a two-sole shoe. My improved unit comprises an extension edge innersole 10, a heel and shank reinforcing piece 12 and a shank stiffener 14. The innersole 10 is made somewhat larger in size than the bottom of the last to be used in making the shoe to provide a marginal or "extension edge" portion for underlying the outturned flange of the upper of a stitchdown shoe. The reinforcing piece 12 is preferably made of fiberboard, leatherboard or other suitable moldable and relatively stiff material and is died out or otherwise cut to a marginal contour corresponding substantially to that of the heel and shank portions of the last and it is secured to the innersole in such a position as to cover the heel and shank portions of the innersole with the exception of the extension edge portion thereof and to leave the latter uncovered for the reception of thread lasting and outsole-attaching stitches. A suitable cement, such as rubber latex, may be employed for attaching the reinforcing piece to the innersole, the cement being preferably applied to both the innersole and the reinforcing piece before these parts are brought together. As shown, the reinforcing piece 12 is attached to the side of the innersole which is to be lowermost so as to face the outsole in the shoe and the shank stiffener 14 is interposed between the innersole and the reinforcing piece. The reinforcing piece is beveled to a thin edge all around, a wide bevel being formed so that when the reinforcing piece is assembled with the innersole 10 the lower surface

of the piece 12 will merge gradually with the surrounding lower surface portions of the inner-sole and thus a smooth, substantially uninterrupted surface will be presented throughout the entire lower side of the unit for the reception of the outsole. The illustrated shank stiffener consists of a wooden shank piece of well-known construction, the shank piece being curved both longitudinally and transversely to correspond to the longitudinal and transverse curvatures of the portion of the last bottom which it is to underlie in the shoe and having its lateral and end surfaces beveled at its lower side to avoid the formation of undesirable sharp ridges in the reinforcing piece and the outsole. However, if desired, a metallic shank stiffener may be employed in place of the wooden shank piece. In any case, however, it is desirable to employ a shank stiffener of substantial thickness so that after the unit has been molded, as will be described, the reinforcing piece will have somewhat more transverse convexity than the innersole and thus, the shank portion of the outer sole, which will be conformed to the reinforcing piece, will have a corresponding amount of transverse convexity therein instead of being substantially flat as in most stitchdown shoes as heretofore made. The shank stiffener is secured in place by means of cement which is applied to the reinforcing piece and to the insole and, as shown, the forward portion of the shank stiffener extends into a notch 16 in the forward extremity of the reinforcing piece which positively prevents lateral displacement of the forward portion of the shank stiffener. After the parts of the sole unit have been assembled the reinforcing piece and the portion of the innersole which overlies it are molded to shape them in conformity with the longitudinal and transverse curvatures of the shank stiffener and of the last bottom. Advantageously, this molding may be accomplished by introducing the assembled parts between molds having suitably shaped molding surfaces, such as the molds 18 and 20 shown in Fig. 3. The molding being preferably accomplished while the cement is tacky and the cement becoming more or less set as a result of the molding pressure, the cement between the layers of the laminated sole unit will assist in preserving indefinitely the molded formation imparted to the unit. The molds 18 and 20, as shown, are substantially smaller in size than the innersole 10 so that the extension edge portion of the innersole will project beyond the molds and will not be acted upon thereby. Consequently, the extension edge portion of the innersole will not be molded and no transverse curvature will be imparted to this marginal portion of the innersole but it will be left substantially flat except where it is curved in a lengthwise direction. Thus more space is provided between the innersole extension and the outturned flange of the upper to facilitate the performance of the thread lasting and outsole stitching operations in the manufacture of a stitchdown shoe in which the innersole unit is incorporated.

In using the above-described sole unit in the manufacture of a three-sole stitchdown shoe (in which the unit is to be employed in place of the usual middle sole) the procedure may be as follows. An upper 24 and a lining 26 (Fig. 4) having been assembled with an insole 28 upon a last 30, the lining 26 is tensioned over the last and the margin of the lining turned inwardly in the forepart and shank portions of the shoe 75

and secured, as by means of cement, in overlasted position upon the insole 28. At the heel end of the shoe the marginal portions of both the lining and the upper may be turned inwardly 5 and secured in overlasted position upon the insole as by means of tacks 32 (Fig. 5). A molded innersole unit comprising a sole member 10, a reinforcing piece 12, and a shank stiffener 14, assembled, secured together and molded as described, is temporarily secured in place over the insole 28. In the forepart and shank portions of the shoe bottom the margin of the upper is flanged outwardly and secured by thread lasting stitches 34 to the extension edge of the sole member 10 of the unit, the stitches 34 extending through the sole member 10 just outwardly of the beveled edge of the reinforcing piece 12. An outsole 36 is then laid and permanently attached, in the forepart and shank portions of the shoe, by means of outseam stitches 38 which extend through the outsole 36, the sole member 10, the outturned flange of the upper 24 and also, as shown, through a welt 40 which overlies the flange of the upper. In the heel-seat portion of the shoe the outsole may be attached by means of nails 42. The shoe is completed by the attachment of a heel 44.

Alternatively, as illustrated in Fig. 6, my improved sole unit may be employed in place of an insole in the manufacture of a two-sole stitchdown shoe. In making such a shoe, an upper 240 is placed upon a last 30, together with an innersole unit constructed as herein described and comprising a sole member 10, a reinforcing piece 12, and a shank stiffener 14. The upper, at least in the forepart and shank portions of the shoe, is flanged outwardly and secured by means of thread lasting stitches 340 to the extension edge of the innersole unit. Thereafter, an outsole 360 is laid and permanently attached by means of outseam stitches 380 which extend through the outsole, the extension edge of the innersole and through the outturned flange of the upper 240.

In either a two-sole or a three-sole stitchdown shoe having my improved innersole unit incorporated therein the reinforcing piece 12 and the shank stiffener 14 will impart a desired stiffness and rigidity to the shank portion of the shoe bottom which is lacking in shoes of this type as ordinarily constructed. As a result of the permanent surface contours imparted to the shank and heel portions of the innersole unit by the molding operation the shoe will not only have better foot-fitting qualities than are usually present in stitchdown shoes but, because of the shape and particularly the transverse convexity of the lower side of the unit in its shank portion, a corresponding shape will be imparted to the shank portion of the outsole so that the latter will compare favorably with shoes of other and more expensive types so far as the shape, character and refinement of the shank portion of the outsole is concerned. In making the shoe, on account of the fact that the reinforcing piece is substantially smaller than the innersole and does not overlap the extension edge portion of the latter, the needle of the thread lasting machine will not have to pierce the tough fiber of the reinforcing piece and thus the thread lasting operation can be satisfactorily performed without danger of breaking the needle. Inasmuch as the fiber piece terminates at some distance inwardly from the edge of the innersole, it will not be visible in the finished edge of the shoe bottom to

detract from the appearance of the shoe. Moreover the fiber reinforcing piece, being located between inner and outer sole members is entirely concealed from view and it is permanently secured in place throughout its entire area in such a manner as to insure that it will effectively perform the function of stiffening the shoe and maintaining permanently the desired form of the shank portion of the shoe bottom.

Having described my invention, what I claim as new and desire to secure by Letters Patent of the United States is:

1. A stitchdown shoe comprising an upper having an outturned flange, an inner sole having an extended margin underlying said outturned flange, stitches extending through the base of the outturned flange of the upper and through said inner sole, a relatively stiff reinforcing piece cemented to the lower side of the shank and heel portions of the inner sole, said piece being coextensive with that portion only of the inner sole which lies within said stitches, a shank stiffener interposed between the inner sole and the reinforcing piece, an outer sole, and stitches securing together said outturned flange and the margins of said inner and outer soles, said reinforcing piece and the portions of said inner and outer soles which are coextensive with said piece being transversely curved to conform to the transverse curvature of the bottom of a last but the extension margin of the inner sole and the corresponding marginal portions of the outer sole

in the shank portion of the shoe having no substantial amount of transverse curvature.

2. A reinforced inner sole unit for a stitchdown shoe comprising an extension edge sole having a transversely curved intramarginal shank portion and transversely straight marginal shank portions, a relatively stiff reinforcing piece secured to the lower side of the shank portion of the said sole inwardly of said marginal portions, and a longitudinally curved shank stiffener interposed between said sole and said reinforcing piece, the margin of said reinforcing piece being formed with a wide bevel providing a thin edge.

3. A reinforced inner sole unit for a stitchdown shoe comprising an extension edge inner sole, a relatively stiff reinforcing piece secured to the lower side of the shank portion of the inner sole, a shank stiffener interposed between said inner sole and said reinforcing piece, the rear and side edges of said reinforcing piece being spaced a substantial distance from the edge of said inner sole, thereby stiffening the intramarginal shank portions of the inner sole and providing uncovered and unstiffened marginal shank portions for underlying the outturned marginal flange of an upper, said reinforcing piece and the portion of said inner sole which is covered thereby each being curved transversely to conform to the transverse curvature of the bottom of a last but the uncovered marginal shank portions of the inner sole being transversely straight.

HARRY N. GRIMES.
